CLAIM

(52) **U.S. Cl.**

I claim the ornamental design for a lid for beverage container, as shown and described.

USPC **D9/447**

DESCRIPTION

(58) **Field of Classification Search**

FIG. 1 is a rear, top, left side, perspective view of a lid for a beverage container.

USPC D6/452-545; D7/300, 321, 392.1, D7/396.2, 500, 507, 509, 510, 511, 900; D9/434-448, 452-455, 682, 685, 694; 215/200, 235, 236, 252, 254, 329, 215/355-364; 220/203.04-203.07, 220, 220/254.1, 254.4, 556, 703, 704, 705

FIG. 2 is a front elevation view of the lid in FIG. 1.

See application file for complete search history.

FIG. 3 is a rear elevation view of the lid in FIG. 1.

(56) **References Cited**

FIG. 4 is a right side elevation view of the lid in FIG. 1, the left side elevation view being a mirror image.

U.S. PATENT DOCUMENTS

FIG. 5 is a top plan view of the lid in FIG. 1.

2,600,478 A 6/1952 Campomar
2,646,670 A 7/1953 Spalding

FIG. 6 is a bottom plan view of the lid in FIG. 1; and, FIG. 7 is a cross-sectional view taken along line 7-7 of FIG. 2, shown at an enlarged scale.

The dominant features of my design reside in the lid's basin, which comprises a valley surrounded by angled walls. The basin ridge slopes downward from the front to the rear of the basin.
